UNITED STATES PATENT OFFICE.

BRUNO MARTIN, OF SAGINAW, MICHIGAN.

BLOWTORCH AND FIRE POT.

Application filed June 24, 1927. Serial No. 201,083.

This invention relates to certain new and useful improvements in blow torches and fire-pots, and more particularly to an accessory readily applied to any style of blow torch or fire-pot to form a safety combustion guard.

The present invention has for its objects among others to provide simple and efficient means, readily accessible to blow torches already in use or as easily applied to new or old torches, by the use of which all danger of fire is obviated. I provide a movably mounted safety combustion guard which constitutes a preventer against igniting nearby articles and thus is a fire protector. It saves labor and at the same time is a protection against wind. This safety guard is formed with a slanting curve rim to catch the unburned oil when the torch is put in operation and keep the flame from igniting the oil in the drip cup.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification and in which—

Figure 1 is a side elevation showing my safety guard in operative position upon the burner tube of a blow torch.

Figure 2 is a semiperspective view with portions broken away.

Figure 3 is an end elevation in detail showing the guard moved to one side, and with a portion thereof broken away.

Like numerals of reference indicate like parts throughout the several views.

Referring to the drawings there is shown a blow torch, which, except as hereinafter described in detail, may be of any of the well known, or approved forms.

1 is the burner tube; the other parts need no detailed description.

Detachably mounted on the forward end of this burner tube, in any suitable manner so as to be quickly and easily applied or removed when desired is my safety guard. This guard 2 comprises a preferably annular member in the general form of a shallow cup or the like the open end of which is surrounded by a bead or the like 3, the mouth 5 of said cup being of less diameter than the

interior of the cup and formed with a sloping or slanting wall 4 as seen clearly in Figures 2 and 3, so provided in order to catch any unburned oil when the torch is put in operation and keep the flame from igniting the oil in the drip cup, the curved formation serving as a safe means of preventing the oil from escaping from the cup under ordinary conditions.

This member 2 is designed to be detachably affixed in position on the burner tube in any suitable manner. In the present instance I have chosen to show it as carried by an arm or the like the inner end of which is designed to be pivotally mounted on the top of the burner tube in any suitable manner and its outer end in the present instance being shown as turned at substantially a right angle to form the member 6, which is received within the member 2, in the present instance being engaged in a notch 7 in the rim of the member 2 and the member 2 and the portion 6 being secured together, in this instance, by a bolt or the like 8 carrying on its outer end a thumb nut 9; this however is but one of many ways in which these two members may be secured together.

The inner end of the arm 5 is pivotally mounted so that it may be swung to the right or the left. In the present instance the said inner end of the arm 5 is mounted to turn upon the vertical screw or the like which is disposed between the arm 11 the outer end of which is upturned as seen at 12 and formed into the forked member 13 forming a rest, such as is usually provided in this form of blow torches, and the member 14 the inner end of which is shown as having the upturned portion 15 on which the inner end of the member 11 rests and secured by the screw or the like 16.

The member 14 may be secured to the outer end of the burner tube 1 in any suitable manner, as, for instance, by means of a band 17 embracing the burner tube and the member 11 and disposed beneath the member 14 as seen in Figure 1, the free ends of the band being extended in parallel relation below the burner tube and united by the bolt 18 and nut 19 as shown.

The attachment can be assembled ready to be applied to the burner tube, and anyone can apply the same in a moment. Normally, the member 2 will be thrown to one side or the other as shown in Figure 3. In use it

is only necessary to move the guard member 2 upon its pivot into position in line with the burner tube as seen in Figure 1 when it serves its purpose effectually as a safety combustion guard.

After the torch is pumped up with air take the safety guard and move it on its pivot into the position shown in Figure 3, then slowly open the needle valve and let the oil run in; the oil will run directly into the drip pan. Swing the safety guard into the position shown in Figure 1, and then light with a match. After the oil in the drip cup has nearly burned out, open the 15 needle valve slowly and have the burner hot for work. Then swing the guard 2 to the right or left out of alignment with the burner tube. In windy or cold weather or when the burner gets cold, swing the guard 20 to the front of the burner tube for a short time to have it hot again without touching the needle valve rod.

In case the workman does not want to use the torch for a time, say half an hour or 25 so, swing the safety guard in front of the burner tube this leaving only a small flame burning, enough to generate the burner and at the same time saving fuel. When ready to use again swing the guard away and

regulate the supply of oil and the flame. 30 This is a simple operation and leaves the soldering iron on the rest, ready for use again.

Modifications in detail may be resorted to without departing from the spirit of the invention or sacrificing any of its advantages. 35

What is claimed as new is;—

1. A blow torch or fire-pot accessory comprising a supporting member with means for detachably mounting it upon the burner tube, a horizontal member pivotally carried thereby, and a guard member depending from the pivoted member whereby the latter may be placed in alignment with the burner tube. 40

2. A blow torch or fire pot accessory comprising a supporting member having means for attachment to a burner tube, a second member pivotally mounted thereon, and a cup-shaped member pending from said second member, the open end of said cup-shaped member being contracted at its open end, said cup-shaped member being movable on the pivot to face the burner tube. 45

In testimony whereof I affix my signature. 50

BRUNO MARTIN.
